(57)

CLAIM

The ornamental design for a torsion bit, as shown and described.

DESCRIPTION

FIG. 1 is a perspective view of a torsion bit.

FIG. 2 is a left view of the torsion bit of FIG. 1.

FIG. 3 is a right view of the torsion bit of FIG. 1.

FIG. 4 is a top view of the torsion bit of FIG. 1.

FIG. 5 is a bottom view of the torsion bit of FIG. 1.

FIG. 6 is a front view of the torsion bit of FIG. 1; and,

FIG. 7 is a rear view of the torsion bit of FIG. 1.
